Atty.

UNITED STATES PATENT OFFICE.

HARRY N. SORENSEN, OF TOLEDO, OHIO.

DOOR-BUFFER.

1,399,164.

Specification of Letters Patent.

Patented Dec. 6, 1921.

Application filed April 18, 1921. Serial No. 482,199.

To all whom it may concern:

Be it known that I, HARRY N. SORENSEN, a citizen of the United States, and a resident of Toledo, in the county of Lucas and State of Ohio, have invented a certain new and useful Door-Buffer; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to door buffers, particularly of the type used in connection with the doors of automobiles, and has for its object the provision of a simple and improved device of this character which is inexpensive in construction, easy of application to a door and casing, and effective in its operation in taking up play and looseness between the door and its casing and holding the door against rattling.

The invention is fully described in the following specification, and while, in its broader aspect, it is capable of embodiment in numerous forms, a preferred embodiment thereof is illustrated in the accompanying drawings, in which,—

Figure 1 is a fragmentary side view of an automobile body with the door and its casing equipped with the invention and with the latter partly open and partially broken away. Fig. 2 is an enlarged edge view of the socket member of the buffer and a portion of a casing member to which attached. Fig. 3 is an inner side view of said buffer member. Fig. 4 is an edge view of the buffer members in interengaged relation, and Fig. 5 is an outer side view of the projecting member of the buffer.

Referring to the drawings, 1 designates an automobile body having a door casing 2, and a door 3 mounted therein.

The socket member of a buffer embodying the invention is designated 4 and is preferably secured to the casing 2 of the door opening. This member is preferably formed in U-shape from sheet metal or it may be cast or otherwise suitably formed, if desired, and forms a receiving socket 5 and has its leg members extended outward and then inward, as shown at 6, to provide a substantially U-shaped socket 7 at each side of the

socket 5. The inner or rear end of each of the sockets 5 is closed by an end part 8. The sockets 7 are intended to receive cushion-blocks 9 of rubber or other suitable cushion material and project at their outer ends beyond the ends of the respective sockets in position to be engaged by the edge flange 10 of the door when closed. The cushion blocks 9 abut at their inner ends against the ends 8 of the sockets and when their outer ends become worn the blocks may be moved outward a desired extent to compensate for the wear and be held in such position by placing suitable shims between the inner ends of the blocks and the socket ends 8 as is apparent. The member 4 may be secured to the casing by screws 11 inserted through openings 12 in the base portion of the dove-tail receiving socket 5 thereof.

The projecting member of the buffer comprises a plate 13 for attaching to a door edge by screws or in any other suitable manner and this plate has a block-like part 14 rigidly projecting outward from its face in position to extend transversely of the door edge to which the plate is secured. A metal band 15, preferably of substantially V-form is mounted around the block 14 and rigidly secured thereto by a pin 16 or in any other suitable manner. The leg portions of the band 15 are spaced laterally from a point near the nose portion of the block to the rear end thereof and the broadest part of the band 15, which forms the projecting member of the buffer, is slightly broader than the width of the socket 5, so that upon entering the same the free end portions of the band member legs are pressed inward by contact with the walls of the socket. The band 15 is made of spring material to facilitate such compressing action and it is preferable to provide a cushion block 17 of rubber or other suitable yielding material between each leg of the band 15 and the portion of the block 14 from which it is spaced. The free ends of the band 15 are turned inward around the ends of the block 17 to prevent a withdrawal of the cushion block from their respective pockets lengthwise of the dove-tail. The blocks are prevented from transverse removal from their pockets by a cross piece 18 which is secured to the block 14 and overlaps the cushion blocks 17.

It is evident that I have provided a simple, efficient and inexpensive form of buffer, the

cushion parts of which may be easily replaced when their effectiveness as cushions is lost, and that the socket member of the buffer also serves as a holder for one or 5 more yielding buffer blocks for the door. It is also evident that with my buffer the projecting member constitutes the yielding spring member of the set instead of the female member, as is customarily the case.

10 I wish it understood that my invention is not limited to any specific construction, arrangement or form of the parts, as it is capable of numerous modifications and changes without departing from the spirit 15 of the claims.

Having thus described my invention, what I claim as new and desire to secure by Letters Patent, is,—

1. A door buffer having a socket member 20 and a projecting member, the projecting member having a rigid block portion, a band looped around the nose of the block portion and having opposed yielding divergent leg portions spaced from the block and adapted 25 to yieldingly coat with the opposed walls of the socket member when entering the same, and cushion blocks disposed between the

rigid block and the yielding leg portions of the band.

2. A door buffer having its socket member 30 forming a socket at a side thereof, and a cushion block adjustably mounted in the socket.

3. A door buffer having its socket member provided with sockets at opposite sides 35 thereof and door cushion blocks adjustably mounted in the sockets and projecting from their outer ends.

4. A door buffer having its socket member formed in U-shape to form a receiving socket 40 for a projecting member and having its legs extended outward and inward to form sockets at opposite sides of the receiving socket, all of said sockets having open outer ends and the side sockets having closed inner ends, 45 and door cushion bumper blocks adjustably mounted in the side sockets with their outer ends projecting beyond the sockets and their inner ends thrust against the closed ends of the side sockets.

In testimony whereof, I have hereunto signed my name to this specification.

HARRY N. SORENSEN.
